UNITED STATES PATENT OFFICE.

ARTHUR A. MERRITT, OF WORCESTER, MASSACHUSETTS, ASSIGNEE TO WILLCOX & GIBBS SEWING MACHINE CO., OF NEW YORK, N. Y., A CORPORATION OF NEW YORK.

PRESSER-FOOT-LIFTING MECHANISM.

1,134,477.

Specification of Letters Patent. Patented Apr. 6, 1915.

Application filed September 30, 1913. Serial No. 792,647.

To all whom it may concern:

Be it known that I, ARTHUR A. MERRITT, of Worcester, Massachusetts, have invented a new and useful Improvement in Presser-
5 Foot-Lifting Mechanism, which invention is fully set forth in the following specification.

This invention relates to presser-foot lifting mechanism for sewing machines, and particularly to that type of such mechanism
10 as is actuated by pressure of the knee of the machine operator.

One object of the invention is to provide such a mechanism having a range of adjustments which will enable the knee lever of
15 the mechanism to be accurately and comfortably positioned to the knee of the particular operator who may be running the machine.

Another object is to allow the sewing machine above the bench or table to be moved
20 up and backward, in tilting the same on its hinges to the bench, without the necessity of disconnecting the presser-foot lifting mechanism.

The invention will be readily understood
25 by reference to the accompanying drawings illustrating what is now considered to be the preferred embodiment thereof, and wherein—

Figure 1 is a front elevation, the table to
30 the under side of which the presser-foot lifting mechanism is fastened being shown in section, and the sewing machine above the table being illustrated in dotted outline; Fig. 2 is an end elevation from the left of
35 Fig. 1; Fig. 3 is a top plan view of the presser-foot lifting mechanism alone; and Fig. 4 comprises detail perspective views of several parts.

5 is a bench or table having an opening
40 therethrough over which a sewing machine
6 illustrated in dotted outline is mounted, a flange 7 on the base plate 8 of the machine fitting within the opening with sufficient
45 looseness to permit the machine to be readily lifted from the table, or to be tilted backward for access to mechanism on the under side of the base plate 8.

9 is a presser-bar carrying a presser foot
10 and a screw pin 11. A vertically movable
50 rod 12 engages the under side of the head of pin 11 to elevate the presser-bar and presser-foot against the tension of the usual spring (not shown) which tends to hold it in contact with the work. One end
55 of a bell-crank lever 13 engages a notch in

the side of the rod 12 to impart lifting movement to the latter, the other end of said lever being connected by a link 14 to one end of a second bell-crank lever 15, the other end of which is connected by a depending link 16 to
60 a third bell-crank lever 17 fulcrumed to a bracket 18 on the lower side of the base plate 8 by a pivot screw 19. As will be apparent, any movement of the sewing machine will carry with it the parts mentioned.
65

20 is the frame-work of a friction clutch power transmitter of the type illustrated in my application for patent filed August 26, 1912, Serial No. 717,182, said framework 20 having two curved depending arms 21 and
70 22, the latter being provided on its outer face with two bosses 23, 24, for the attachment of the presser-foot lifting mechanism about to be described.

26 is a skeleton-plate or frame secured to
the arm 22 by screws 27, 28, engaging
screw-threaded openings in the bosses 23 and
24 respectively. An arm 29, preferably
75 formed integrally with the plate 26, extends
at right angles to the main body of the latter
across the edge of the arm 22, and constitutes
80 a support to which a lever 30 is fulcrumed
at its lower end by a pivot-screw 31,
said lever 30 having at its upper end a broad-
ened face 32 adapted to be contacted by the
85 lower end of bell-crank lever 17. When the
sewing machine is tilted back from its up-
right position, the lower end of bell-crank
lever 17 swings upwardly in the arc of a
90 circle out of engagement with the face 32
of the lever 30; to facilitate the repositioning
of the bell-crank lever 17 with relation
to the face 32 when the machine is again
95 swung to its upright position, the forward
edge of the face 32 is rounded at 33, where-
by the lower end of the bell-crank lever 17
may ride up said inclined edge onto the flat
surface 32.

35 is a vertical rock shaft journaled in
lugs 36 and 37 on the plate or frame 26.
100 To the upper end of shaft 35, above the lug
36, there is fixed a lever 38; the longer arm
of said lever at one side of its fulcrum is
provided with a seat 39 for a spring shortly
105 to be described, and at its outer end is con-
nected by a link 40 to the upper end of the
lever 30 heretofore mentioned. The shorter
arm or lever 38 at the other side of its ful-
crum has a depending stop lug 41 adapted
110 to contact the edge of the lug 36 and there-

by limit the movement of the lever 38 under the influence of a coiled spring 42 which rests at one end in the seat 39, and at its other end in a seat 43 in the plate 26. A collar 44 is fastened to the lower end of shaft 35.

The knee-lever or arm is made in two parts, an inner part 45 having at its inner end a split socket embracing the rock shaft 35 and adapted to be clamped thereon by tightening the set-bolt 46; and an outer part 47 having a depending rounded and broadened extension 48, the rounded surface of which is adapted to be engaged by the right knee of an operator sitting before the machine and operating the same. The parts 45 and 47 of the knee-lever are extensibly connected together by means of a rib 49 on the inner face of 47 slidably engaging between two ribs 50, 50, on the part 45, a set-bolt 51 carried by the part 47 working through a slot 52 in the inner part 45. It will thus be apparent that by loosening the bolt 51 and sliding the part 47 with relation to the part 45, the length of the knee-lever may be adjusted as desired; and furthermore that by loosening the set-bolt 46, the knee-lever may be moved vertically along the rock shaft 35 to any desired elevation and turned about the same to any desired radial position that may be found to be most comfortable to the particular operator in charge of the machine.

What I claim is:—

1. The combination with a machine part to be moved under control of knee-pressure, of an upright rotatable shaft, a knee-lever adjustably secured to said shaft, and connections to the machine part for moving the latter upon actuation of the knee-lever.

2. The combination with a machine part to be moved under control of knee-pressure, of an upright rotatable shaft, a knee-lever adjustable to any desired elevation along said shaft, and connections to the machine part for lifting the latter upon actuation of the knee-lever.

3. The combination with a machine part to be moved under control of knee-pressure, of an upright rotatable shaft, a knee-lever adjustable longitudinally of and radially to said shaft, means for securing the knee-lever to the shaft in any position of the adjust-

ment of the former, and connections to the machine part for lifting the latter upon actuation of the knee-lever.

4. The combination with a presser-foot, of an upright rotatable shaft, an extensible knee-lever adjustable longitudinally of and radially to said shaft, means for securing the knee-lever to the shaft in any position of the adjustment of the former, and connections to the presser-foot for lifting the same upon actuation of the knee-lever.

5. The combination with a presser-foot, of an upright rotatable shaft, an extensible knee-lever secured to said shaft, and connections to the presser-foot for lifting the latter upon actuation of the knee-lever.

6. The combination with a presser-foot, of an upright rotatable shaft, a knee-lever adjustable on the shaft, an arm on the shaft, a second lever, a link connecting said arm and second lever, and connections to the presser-foot actuated by said second lever to lift the presser-foot upon actuation of the knee-lever.

7. The combination with a sewing-machine and its presser-foot, of an upright shaft, a knee-lever on the shaft, an arm on the shaft, a second lever, a link connecting said arm and second lever, a third lever fulcrumed to and movable with the sewing-machine and lying in the path of movement of and adapted to be actuated by the second lever when the sewing-machine is in its normal operating position, and connections from said third lever to the presser-foot.

8. The combination with a sewing-machine and its presser-foot, of a lever, knee-actuated means for moving said lever, a second lever fulcrumed to and movable with the sewing-machine, said second lever being unfastened to the first mentioned lever but being adapted in the normal position of the machine to lie in the path of movement of and be actuated by said first-named lever, and connections from said second lever to the presser-foot for lifting the latter.

In testimony whereof I have signed this specification in the presence of two subscribing witnesses.

ARTHUR A. MERRITT.
